UNITED STATES PATENT OFFICE.

REUBEN F. BARKER, OF PORTLAND, OREGON.

FLUID-COOLED ROTARY VALVE FOR INTERNAL-COMBUSTION ENGINES.

Application filed February 5, 1925. Serial No. 7,054.

My invention relates to internal combustion engines and has particularly to do with the valve mechanism thereof. One of the particular objects of my invention is to improve further the rotary valve for explosive engines patented by myself January 1, 1918, No. 1,251,953.

In this connection one of the main improvements of my present invention is to provide each cylinder with an independent rotary valve, and furthermore to increase the size of the passageways through said valve, relatively. This improvement permits the actuating fluid to be passed to the cylinder without unnecessary interruption and in substantial undiminished volume. The exhaust gases also are permitted to be ejected from the cylinders with a very slight amount of back pressure, to cause a thorough scavenging of the burned gases.

In my present invention said independent valves are arranged side by side and are connected by a common operating element. By arranging the valves in this manner and arranging the driving connection so that each valve is rotated but once in each cycle of the engine, the ports in said valve can be increased so as to cover a greater portion of the circumference of the cylindrical valve body, than heretofore. As the size of the port regulates the timing of the valve operations, in this type of continuously rotating valve, the arrangement of said ports, so as to cover a greater portion of the circumference of the valve, thus permits the timing to be made more accurately, with less requirement for close adjustment. The valve also opens and closes more quickly, relatively to the stroke of the piston in the cylinder, and thus permits the cylinder ports to be held completely open for a longer period, relatively to the stroke of said piston. Play between the ports and variation in size, due to wear, will also not affect the timing of the valve operations as much as it would in a valve structure such as is shown by my previously patented rotary valve.

A further object of my present invention is to provide connecting devices between the operating mechanism of each of the independent valves, and a common driving element whereby the valve operations for all of the cylinders can be readily advanced or retarded in unison, relatively to the motion

of the crankshaft. To this end said valve operating devices preferably consist of a driving shaft, provided with worm and worm gears of the type known as spiral gears. Said worm gears are mounted on each of said valve operating mechanism so that by shifting said common drive shaft longitudinally the timing of all of the valves will be advanced or retarded to an equal degree due to the lead of the thread on said worm.

A further object of my present invention is to provide means adapted to hold that portion of the face of the valve adjacent the seat of the cylinder port, firmly against said port, at least during the instant the gas is ignited in said cylinder, so as to prevent gas from escaping into the valve bore of the cylinder. Said means preferably consist of a holding-down mechanism, a part carried by the valve and part carried by the bore of the cylinder, which is arranged to periodically tend to move said valve towards the cylinder port to seat the same firmly in place and which relieves the pressure during other positions of the valve. I also show devices by which the entire valve is mounted eccentrically to the bore, the eccentric throw being arranged to hold the valve in the bore in such a position that it bears tightly against the port at all periods of the cycle. Said devices eliminate the frictional resistance of tight packing about said valve, which would otherwise be required.

A further object of my present invention is to arrange the water jacket for each valve so that the bottom of said water jackets or fluid passageways are arranged below the plane of the inlet and outlet ports. If the water supply should thus become exhausted a portion of the cooling fluid would be retained in said water jacket or fluid passageway to cool the exposed surfaces of the valve until said quantity is displaced by another volume of said fluid.

A further object of my present invention is to provide the face of the valve covering the cylinder port, at the instant the gas charge is ignited, with grooves scored in its face which substantially encircle said face thereby to retard the escape of the expanding gases through the clearance between the valve and wall of the chamber.

A further object of my invention is to

range the passageways for the gases and for the cooling fluid so that the actuating fluid can be introduced and removed at one end of the rotary valve and the cooling fluid can be introduced and removed at the opposite end. Intake and exhaust manifolds are arranged in the first mentioned end of the valves and a manifold for the cooling fluid is arranged at the opposite end.

10 A further, and main object of my invention is to provide for the efficient cooling of each valve of the internal combustion engine. I attain this object by providing a continuous passage-way for such fluid, such 15 passage-way formed of concentric tubes, the bore of one tube constituting the inlet, and the bore of the other the outlet, for said cooling fluid, thereby to assure that the circulation of the cooling fluid is facilitated 20 and promoted, and that each valve will be efficiently and uniformly cooled, thus to prevent excessive heating of the valve with consequent binding or "sticking" within the housing which is a common characteristic 25 of, and frequently a source of trouble in this type of valve; and my invention also tends to prevent unequal expansion of the valve, due to unequal cooling which sets up stresses and strains which tend to increase 30 the wear of the valve housing with attendant repairs and delays.

The further details of construction and mode of operation of my invention are hereinafter described with reference to the accompanying drawings.

In said drawings:

Fig. 1 is a vertical longitudinal section taken along the center of the aligned cylinders and extends transversely through the 40 valves, said figure illustrates a four cylinder engine with the cylinders and valves arranged at approximately the beginning of the four valve events, in which the cycles of internal combustion engines are commonly divided;

Figs. 1^a and 1^b are respectively cross-sections through one end of a valve and illustrate diagrammatically two phases of the means whereby pressure and resistance are applied to the face of the valve positioned opposite the cylinder port at the instant the gas charge is ignited, said pressure tending to hold the valve closely against its seat on said port, said pressure being relieved during the other positions of the valve;

Fig. 2 is the horizontal section taken on the line 2—2 of Fig. 1, the arrows diagrammatically indicate the path of the actuating and cooling fluids through said valves;

Fig. 3 is a vertical section taken on the line 3—3 of Fig. 2 and shows the worm and worm-gear connections between the common driving shaft and separate independent valves;

Fig. 4 is a vertical section taken on a line

4—4 of Fig. 1, the arrows in this figure also diagrammatically indicate the path of the actuating and cooling fluids;

Fig. 5 is a fragmentary figure taken on the line 5—5 of Fig. 3;

Fig. 6 is a fragmentary section taken on the line 6—6 of Fig. 4 with arrows showing the direction of the flow of the cooling fluid;

Fig. 7 is a perspective view of one valve element with one-half the Oldham coupling disconnected therefrom;

Fig. 8 is a similar perspective view of the valve turned end for end and showing the opposite side of said valve;

Fig. 9 is an enlarged longitudinal sectional view taken on the line 9—9 of Fig. 1;

Fig. 10 is a transverse section taken on the line 10—10 of Fig. 9;

Fig. 11 is a longitudinal section similar to Fig. 9 but shows an alternative arrangement for holding the valve relatively to the cylinder port to prevent leakage of gas into the bore of the cylinder in which the valve rotates;

Fig. 12 is a cross-section taken on the line 12—12 of Fig. 11; and

Fig. 13 is a cross-section taken on the line 13—13 of Fig. 11.

My invention is shown as embodied in a multi-cylinder engine of the four cycle type. Said engine comprises cylinders 1^a, 1^b, 1^c and 1^d in which the pistons 2^a, 2^b, 2^c and 2^d, respectively, reciprocate. Separate valves 3^a, 3^b, 3^c and 3^d, respectively control the admission and emission of the gases to and from said cylinders 1^a, 1^b, 1^c and 1^d, through the cylindrical ports 4^a, 4^b, 4^c and 4^d in said cylinders, respectively.

All of said valves 3^a, 3^b, 3^c and 3^d are structurally the same and thus I will describe in detail merely one of said valves and will refer, with similar reference characters, to the corresponding parts in the other of said valves. Said valves are journaled in bores in said engine which communicate with the working barrels of said cylinder through the cylinder ports 4^a, 4^b, 4^c and 4^d. As is shown in Figs. 1 and 2, said cylinders are in line and said valves 3^a, 3^b, 3^c and 3^d therefor lay side by side transversely of said cylinders.

Each of said valves 4^a, 4^b, 4^c and 4^d carries a worm gear of the type known as a spiral gear, numbered respectively 5^a, 5^b, 5^c and 5^d. Said worm gears drive said valve through Oldham couplings 6^a, 6^b, 6^c and 6^d, respectively. Each of said worm gears is carried upon a roller bearing 7^a, 7^b, 7^c or 7^d. Said roller bearings are mounted upon hollow trunnions 8^a, 8^b, 8^c and 8^d, which are integral with and extend laterally from the housing 9, which constitutes a covering for said couplings, bearings, worm gears, and for the common drive shaft 10, which carries the

worms 10^a, 10^b, 10^c and 10^d which mesh with and drive the worm gears 5^a, 5^b, 5^c and 5^d, respectively, said housing is shown in section in Fig. 4. The tubular water conduits 11 from each of said valves are also journaled in said housings, packing 12 is arranged at both sides of the radial outlets 13 therein, as shown in Fig. 2. Said housing carries the cooling fluid manifold 14, as shown in Fig. 4. Said manifold has outlet openings 14^a, which communicate with the radial outlets 13 which extend through said tubular conduit 11 in the manner shown in Fig. 4.

Within said tubular conduit 11 is a smaller sized conduit 15 which has a flange 15^a at its outer extremity, which completely fills the bore of the tubular conduit 11. The bore of said smaller tubular conduit 15 extends completely therethrough and forms a passageway for the cooling fluid which is completely separated from the passageway formed by the periphery of the smaller conduit 15. The inlet aperture 14^b communicates with the bore in said smaller sized conduit 15, as shown in Fig. 4.

The apertures 14^a and 14^b in the cooling fluid manifold are located at a point above the major part of the valve so that a substantial amount of cooling fluid will be entrapped within the valve so that if the supply of cooling fluid should become depleted, the cooling fluid thus entrapped would be sufficient to substantially cover the exposed portions of the valve.

The connecting passageways 14^c and 14^d which connect said apertures 14^a and 14^b with the respective outlet and inlet ends of the cooling fluid passageway, are arranged vertically and constitute stand pipes adapted to prevent the displacement of the cooling fluid as previously referred to.

Each of said valves comprise a cylindrical body which is provided with a passageway for the incoming gases, a passageway for the exhaust gases, and a continuous passageway adjacent said gas passageways for the cooling fluid. The arrangement of the passageways in this manner permits the heat of the exhaust gases to be removed in part so as to prevent said excessive heat from binding said valves in their seats, due to distortion.

As can be seen in Figs. 1 and 2, the intake passageway 16 in each of said valves occupy a cylindrical bore, extending substantially through the valve and terminates in a port 17. Said port opens to the periphery of said valve and occupy a sector of said cylinder, which is substantially one-fourth of the circumference. The exhaust passageway 18 partially surrounds the intake passageway 16 and also terminates in a port 19 which occupies substantially one-fourth of

the circumference of said valve. Said bores 65 are separated by a hollow wall section 20.

The passageway for the cooling fluid comprises the bore of the conduit 15, which terminates in the hollow passageway 20 between the bores 17 and 19. Said passageway 70 20 terminates in the hollow head 21 which permits the cooling fluid to circulate around the exterior of the exhaust conduit 18 and to communicate with the hollow head 23 at the opposite end of the valve to the head 75 21. Said head 23 communicates with the bore of the conduit 11 and the cooling liquid is emitted through the radial holes 13 through the standpipe section 14^c to the outlet aperture 14^a in the manifold 14 for the 80 cooling fluid. The passageway for said cooling fluid thus is continuous through the valve.

The cooling fluid enters and is emitted from points adjacent each other at the same 85 side of said valve. The passageway extends through the valve longitudinally from one end to the other and doubles back upon itself. The passageway in said valve for the cooling fluid parallels the passageway for 90 the gases. Said passageways are arranged to remove a substantial portion of the heat from the exhaust gases emitted by the cylinder and the exhaust passageway is arranged relatively to the intake passageway 95 so that sufficient heat is given thereto to partially, if not wholly, gasify the combustible gases passing through said intake passageway, thus to assist in the combustion thereof in the cylinder.

All of the exhaust passageways 18 for the separate valves communicate with the exhaust manifold 24. The intake passageways are longer than the exhaust passageways and extend through said exhaust manifold, as shown in Fig. 4. All of said intake passageways are connected to the intake manifold 25 in the common manner. The heat of the gases emitted through the exhaust manifold are permitted to act upon 110 the intake pipes to heat the same for a short length thus to cause the gasifying action previously referred to.

As is shown in exaggerated fashion in Figs. 9 and 10, portions 26 and 26^a at the ends of said valve member and at each side of the intake and outlet bores in the valve are arranged eccentric relatively to the remainder of the valve. Said figures exaggerate the clearances between the valve and the bore for the purpose of illustration.

As shown in said figures, when the intake and outlet ports are arranged diametrically opposite the cylinder port 4^d, as in the cylinder 1^d in Fig. 1, the valve is arranged so that the shoes 27 and 27^a bear against the eccentric portions 26 and 26^a and tend to move the valve towards the cylinder ports

4^a, and thus hold said valve tightly against said ports, to prevent leakage thereby. Said shoes 27 and 27^a are adjustable by placing shims 28 and 28^a of different thicknesses beneath the holding-down brackets 29 and 29^a. Said brackets being held in place by studs 30 and 30^a.

5 About the point 31 which coincides with the cylindrical port 4^a, at this moment, I 10 arrange sealing grooves 32, which tend to prevent leakage of gas between the valve and the bore. As shown in Fig. 8, said sealing grooves 32 are formed in a closed pattern about said point 31.

15 At each side of the ports 17 and 19, I mount expandible sealing rings 33 and 33^a to prevent leakage longitudinally of said valve. Said sealing rings are mounted at each 20 side of the eccentric portions 26 and 26^a and provide an extremely efficient sealing device without building up excessive friction to retard the rotation of said valve.

25 I provide a means for timing all of said valves uniformly by threading the end-caps 34 and 34^a in which the ends of the common driving shaft 10 is journaled. Said shaft 10 is driven by the chain 35 mounted over the sprocket 36, keyed to said shaft 10, as shown in Fig. 5, and it is to be understood 30 that said chain 35 is connected to the crank shaft for said engine, in the common manner, so that said valve can be maintained in synchronism with said shaft.

35 By providing intermeshing worms and worm gears, carried in part by said shaft and in part by said valves 3^a, 3^b, 3^c and 3^d, I am able to advance or retard the timing of said valves uniformly by adjusting said shaft 10 longitudinally. Each one of said 40 end caps 34 or 34^a may be backed off slightly and the other cap tightened correspondingly to produce this change in timing by causing the shaft 10 to be adjusted longitudinally. Due to the lead in the teeth of the 45 worm, this will cause the worm gears to be given a partial rotation and said valves being connec'ted with the crankshaft, will thus be advanced or retarded relatively thereto, by said adjustment.

50 In Figs. 11, 12 and 13, I show an alternative arrangement by which the valve 40 may be arranged relatively in the bore 41 in the cylinder 42, thereby to tend to seat tightly against the cylinder port 43 and thus prevent the escape of gases around said valve. In the devices shown in said figures, the valve is arranged to rotate about an axis x which is not coincident with the axis y of the bore. Said valve 40 is mounted in two 55 removable bearings 44, which are shown as containing balls 44^a, but it is to be understood that said removable bearings might consist of tapered roller bearings or sleeve bearings. Said removable bearings are 60 mounted in recesses 45 at the ends of the

bore 41. Said recesses are mounted eccentric, relatively to said bore thus the valve 40 rotates so that all of the clearance is at the top of the valve, as shown in Fig. 13. The amount of clearance between said valve 70 and said bore is greatly exaggerated and in practice would hardly exceed ten one-thousandths of an inch and would preferably be approximately about five one-thousandths of an inch. By mounting the valve in this 75 manner a substantial amount of clearance can be provided about said valve to provide for easy running, but the valves fit very closely against said port to prevent leakage.

80 All of the valves 3^a, 3^b, 3^c and 3^d are assumed to be rotating in a clockwise direction, as viewed in Fig. 1. The cylinders 1^a, 1^b, 1^c and 1^d and their respective pistons and valves are in the positions corresponding, respectively, to the commencement of intake, compression, exhaust and expansion periods in a four-cylinder four-stroke cycle engine. In cylinder 1^a the piston 2^a is at upper dead center and the valve 3^a is turning clockwise so that the inlet port 17 is just 90 commencing to register with the cylinder port 4^a to permit actuating fluid to be admitted into the cylinder above the piston 2^a. In cylinder 1^b the piston 2^b is at lower dead center and the valve in its rotation has just 95 cut off the outlet port 19 and thus the compression stroke is just commencing. In cylinder 1^c the piston 2^c is at lower dead center and the gases in said cylinder above the piston are escaping through the outlet port 19. 100 In cylinder 1^d the piston 2^d is at upper dead center where the gases are ignited and the resultant expansion forces said piston 2^d downward on its power stroke.

105 It will be noted that the ports 17 and 19 of each of the valves are substantially wider than the related cylinder ports 4^a, 4^b, 4^c and 4^d. A slight variation, therefore, in the width of the valve ports makes little difference in the amount, or the timing of the admission or emission of the gases therethrough into or from the cylinder. In other words, if the valve ports 17 and 19 were only 110 as wide as the cylinder ports, a slight variation in the registration thereof would have 115 a substantial effect upon the timing of the interval during which the ports of the valve and the cylinder are in proper co-operative registration, and thus would substantially effect also the amount of the gases admitted 120 into, or emitted from the cylinder.

125 The gases admitted to a cylinder are received from the intake manifold 25 and are distributed into the various inlet passageways 16 which are substantially concentric bores in the valves. Said gases completely fill said passageway 16 and its port 17, and thus when the ports become in registration with the cylinder port 4^a, said gases are admitted into the cylinder and said 130

valve is timed so that the gases are admitted slightly after the piston reaches upper dead center in the cylinder. Said port remains open until the piston reaches lower dead center on the succeeding down stroke. The up stroke of the piston compresses the gases and when said piston reaches approximately upper dead center, said gases are ignited. The pressure built up within the cylinder, due to the ignition and resultant expansion of the gases, tends to lift the valve off of its seat upon the cylinder port, and also tends to escape about said valve. The rings 33 and 33^a, which extend about the ends of the valve, tend to prevent said leakage. The sealing grooves 32 which form a closed pattern about the point 31, which is in registration with the cylinder port at the time of ignition, also tends to prevent leakage from the said cylinder port. Said sealing grooves pick up a certain amount of oil as they rotate within the bore of the cylinder and the oil thus collected tends to form with the bore in the cylinder a sealing medium about said point 31. I also provide shoes 27 and 27^a, previously referred to, which bear against the eccentric portions 26 and 26^a, respectively, said shoes, by bearing against the eccentric portions, tend to hold the valve tightly upon the cylinder port and thus also tend to prevent leakage about the said valve. The eccentric portions in Figs. 11 to 13 also serve the same purpose.

The succeeding down stroke or power stroke causes the engine to be given sufficient power to carry it through the next three periods, in the common manner. Shortly before the piston reaches lower dead center, the exhaust port 19 becomes in registration with the cylinder port, and thus permits the gases, under compression, to be emitted from the cylinder. Said gases pass through the longitudinal exhaust passageway 18 about the intake passageway 16 and pass into the exhaust manifold 24.

I claim:

1. In an internal combustion engine comprising a series of compression cylinders, an independent rotary valve controlling each cylinder, the valves being arranged side by side, each of said valves being provided with intake and exhaust passageways, and intake and exhaust manifolds with which the intake and exhaust passageways of all the valves are respectively connected, each of said valves being further provided with a passageway for cooling fluid, the latter passageway extending parallel with said gas passageways, doubling back, admitting and emitting cooling fluid at one end of said valve

2. In an internal combustion engine, comprising a series of compression cylinders, an independent rotary valve controlling each cylinder, the valves being arranged side by

side, each of said valves being provided with intake and exhaust passageways, intake and exhaust manifolds with which the intake and exhaust passageways of all the valves are respectively connected, the ports of said intake and exhaust passageways being separated by a hollow radial longitudinal wall, each of said valves being further provided with a passageway for cooling fluid, the latter passageway extending parallel with said gas passageways, doubling back, admitting and emitting cooling fluid at one end of said valve, and communicating with said hollow wall.

3. In an internal combustion engine comprising a series of compression cylinders, an independent rotary valve controlling each cylinder, the valves being arranged side by side, each of said valves being provided with intake and exhaust passageways, and intake and exhaust manifolds with which the intake and exhaust passageways of all the valves are respectively connected, each of said valves being further provided with a passageway for cooling fluid, the latter passageway extending parallel with said gas passageways, doubling back, admitting and emitting cooling fluid at one end of said valves, said intake and exhaust manifolds being located at one end of said valves, and the inlet and outlet openings of said cooling fluid passageway being located at the opposite end of said valves.

4. In an internal combustion engine comprising a series of compression cylinders, an independent rotary valve controlling each cylinder, the valves being arranged side by side, each of said valves being provided with intake and exhaust passageways, and intake and exhaust manifolds with which the intake and exhaust passageways of all the valves are respectively connected, said intake passageways extending through the exhaust manifold, each of said valves being further provided with a passageway for cooling fluid, the latter passageway extending parallel with said gas passageways, doubling back, admitting and emitting cooling fluid at one end of said valve said intake and exhaust manifolds being located at one end of said valves, and the inlet and outlet openings of said cooling fluid passageway being located at the opposite end of said valves.

5. In an internal combustion engine comprising a series of compression cylinders, an independent rotary valve controlling each cylinder, the valves being arranged side by side, each of said valves being provided with intake and exhaust passageways, and intake and exhaust manifolds with which the intake and exhaust passageways of all the valves are respectively connected, said intake passageways extending through the exhaust manifold, the ports of said intake and

- exhaust passageways being separated by a hollow radial longitudinal wall, each of said valves being further provided with a passageway for cooling fluid, the latter passageway extending parallel with said gas passageways, doubling back, admitting and emitting cooling fluid at one end of said valve, and communicating with said hollow wall.
10. In an internal combustion engine, a valve provided with a cooling fluid passageway arranged alongside the exhaust passageway so as to cool the latter, and means for holding a portion of the cooling fluid in its passageway until displaced by another volume of the cooling fluid.
15. In an internal combustion engine, a valve provided with a cooling fluid passageway arranged alongside the exhaust passageway so as to cool the latter, the outlet port of said cooling fluid passageway being located in a plane above the bottom of said cooling fluid passageway, whereby a portion of the cooling fluid is constantly retained in said passageway until displaced by another volume of said fluid.
20. In an internal combustion engine, a valve provided with a cooling fluid passageway arranged alongside the exhaust passageway so as to cool the latter, the inlet and outlet ports of said cooling fluid passageway being located in a plane above the bottom of said cooling fluid passageway, whereby a portion of the cooling fluid is constantly retained in said passageway until displaced by another volume of said fluid.
25. In an internal combustion engine, a cylindrical rotary valve, provided with longitudinal intake and exhaust passageways for the working fluid, and a passageway for cooling fluid arranged alongside of said exhaust passageway, the cooling fluid passageway being connected with two tubes mounted concentrically one within the other, and concentric with the axis of rotation of the valve, one of said tubes serving as an intake, the other as an outlet for said cooling fluid.
30. In an internal combustion engine, a cylindrical rotary valve, provided with longitudinal intake and exhaust passageways for the working fluid, and a passageway for cooling fluid arranged alongside of said exhaust passageway, the cooling fluid passageway being connected with two tubes mounted concentrically one within the other, and concentric with the axis of rotation of the valve, one of said tubes serving as an intake, the other as an outlet for said cooling fluid, said tubes terminating in a plane located above the bottom of said cooling fluid passageway, whereby a portion of the cooling fluid is re-
- tained in said passageway until displaced by another volume of said cooling fluid.
35. In an internal combustion engine, a compression cylinder, a rotary valve controlling said cylinder, the valve being provided with gas intake and exhaust passageways and with intake and exhaust manifolds, said intake passage-way extending through the exhaust manifold and said valve being provided with a passage-way for cooling fluid, the latter passage-way extending parallel with said gas intake passage-way.
40. In an internal combustion engine, a compression cylinder, a rotary valve controlling said cylinder, the valve being provided with gas intake and exhaust passage-ways and with intake and exhaust manifolds, said intake passage-way extending through the exhaust manifold, the ports of said intake and exhaust passage-ways being separated by a hollow radial longitudinal wall and said valve being provided with a passage-way for cooling fluid, the latter passage-way extending parallel with said gas intake passage-way.
45. In an internal combustion engine, a compression cylinder, a rotary valve controlling said cylinder, the valve being provided with gas intake and exhaust passage-ways and with intake and exhaust manifolds, said intake passage-way extending through the exhaust manifold, the ports of said intake and exhaust passage-ways being separated by a hollow radial longitudinal wall, said valve being provided with a passage-way for cooling fluid, the latter passage-way extending parallel with said gas intake passage-way and said intake and exhaust manifolds being located at one end of said valves, and the inlet and outlet openings of said cooling fluid passage-way being located at the opposite end of said valves.
50. In an internal combustion engine, a compression cylinder, a rotary valve controlling said cylinder, the valve being provided with gas intake and exhaust passage-ways and with intake and exhaust manifolds, said intake passage-way extending through the exhaust manifold, the ports of said intake and exhaust passage-ways being separated by a hollow radial longitudinal wall, said valve being provided with a passage-way for cooling fluid, the latter passage-way extending parallel with said gas intake passage-way then doubling back and admitting and emitting cooling fluid at one end of said valve and said intake and exhaust manifolds being located at one end of said valves, and the inlet and outlet openings of said cooling fluid passage-way being located at the opposite end of said valves.
55. In an internal combustion engine, a compression cylinder, a rotary valve controlling said cylinder, the valve being provided with gas intake and exhaust passage-ways and with intake and exhaust manifolds, said intake passage-way extending through the exhaust manifold, the ports of said intake and exhaust passage-ways being separated by a hollow radial longitudinal wall, said valve being provided with a passage-way for cooling fluid, the latter passage-way extending parallel with said gas intake passage-way then doubling back and admitting and emitting cooling fluid at one end of said valve and said intake and exhaust manifolds being located at one end of said valves, and the inlet and outlet openings of said cooling fluid passage-way being located at the opposite end of said valves.
60. In an internal combustion engine, a compression cylinder, a rotary valve controlling said cylinder, the valve being provided with gas intake and exhaust passage-ways and with intake and exhaust manifolds, said intake passage-way extending through the exhaust manifold, the ports of said intake and exhaust passage-ways being separated by a hollow radial longitudinal wall, said valve being provided with a passage-way for cooling fluid, the latter passage-way extending parallel with said gas intake passage-way then doubling back and admitting and emitting cooling fluid at one end of said valve and said intake and exhaust manifolds being located at one end of said valves, and the inlet and outlet openings of said cooling fluid passage-way being located at the opposite end of said valves.

REUBEN F. BARKER.
